UNITED STATES PATENT OFFICE.

EMERY G. RESSLER, OF STEVENS POINT, WISCONSIN.

DESIGN FOR A VIOLIN-BRIDGE.

50,113.

Specification for Design.

Patented Dec. 26, 1916.

Application filed October 13, 1916. Serial No. 125,514. Term of patent 14 years.

To all whom it may concern:

Be it known that I, EMERY G. RESSLER, a citizen of the United States, residing at Stevens Point, in the county of Portage and State of Wisconsin, have invented a new, original, and ornamental Design for Violin-Bridges, of which the following is a specification, reference being had to the accompanying drawing, forming part thereof.

Figure 1 is a perspective view of a violin

bridge illustrating my new design, and Fig. 2 is a bottom plan view, showing my new design. Fig. 3 is an edge view.

I claim:

The ornamental design for a violin bridge, as shown.

EMERY G. RESSLER.

Witnesses:

L. J. N. MURAT,

ALICE ROSENOW.
